PAGE 3

Fig. 4

FIG. 1 is a front elevation view of a combined warning light and siren showing my new design;

FIG. 2 is a top view of same;

FIG. 3 is a side elevation view of same, taken at 90° from the view of FIG. 1; and

FIG. 4 is a bottom view of same.

The dominant features of my design reside in the portions shown in full lines.

I claim:

The ornamental design for a combined warning light and siren, as shown and described.
